UNITED STATES PATENT OFFICE.

JOHN W. DALMAN, OF CHICAGO, ILLINOIS, ASSIGNOR TO AMERICAN STEEL FOUNDRIES OF CHICAGO, ILLINOIS, A CORPORATION OF NEW JERSEY.

BRAKE-BEAM SAFETY-HANGER.

1,295,276.

Specification of Letters Patent. Patented Feb. 25, 1919.

Application filed March 22, 1917. Serial No. 156,594.

To all whom it may concern:

Be it known that I, JOHN W. DALMAN, a citizen of the United States, and resident of Chicago, in the county of Cook and State 5 of Illinois, have invented certain new and useful Improvements in Brake-Beam Safety-Hangers, of which the following is a specification.

My invention relates to car brakes and has 10 particular reference to a novel emergency support for brake beams.

In the prior patents to Elliott No. 1,147, 793 and Weinland No. 1,165,733 different forms of emergency supporting devices 15 were disclosed. The present invention has for its object the provision of a supporting device so connected to the car truck as to enable its economical manufacture and simple operation.

20 In practically all of the forms of car trucks at present commonly in use provision is made for the connection of adjacent side frames by means of a commercial channel or similar standard shape. As 25 a means for supporting the bar, which is adapted to underlie the brake beams, I provide loops which may be struck out of the web of the connecting member. Preferably two loops are provided at each end of the 30 channel; that is, at each side of the truck. A bar is longitudinally slidable in these loops and is suitably retained in proper position.

The invention will be more readily understood by reference to the accompanying drawings wherein,

Figure 1 is a sectional view through a truck to which my invention has been applied;

40 Fig. 2 is a plan view of the channel shaped spring plank to which the emergency supporting bars have been applied;

Fig. 3 is an edge view thereof partly in section, and,

45 Fig. 4 is a view similar to Fig. 3 showing a slight modification.

In the drawings it will be seen that the side frames 10 are connected by means of a channel shaped spring plank having a web 50 11, and flanges 12. Near each end of the

channel 11 provide a pair of loops 13, which, in this instance are shown as being formed from metal displaced from the web 11 of the channel. Of course the loops may be provided in another manner if desired. A 55 bar 14 is located in the loops being longitudinally slideable therein and of such length as to underlie the brake beams indicated at 15 in Fig. 1. The bars are held in proper position by the vertical pin or 60 bolt 16 which extends through the channel and bar.

In the construction of Fig. 4 the spring plank is of the same section and has a web 17, and flanges 18. The web is slotted at the 65 proper points and angular loops 19 provided therein suitably shaped to accommodate a bar in the form of an angle 20. A bar of this shape gives greater resistance to bending for the same weight of metal. 70

Other modifications such as may suggest themselves to those skilled in the art may be made without departure from the spirit of my invention.

I claim:

1. In a car truck, the combination of side frames, a spring plank connecting the side frames, said plank being provided with loops struck out from the horizontal portion thereof, and a bar mounted in the loops at 80 each end of said plank, substantially as described.

2. In a car truck, the combination of side frames, a transverse channel connecting same, a pair of loops struck out of the web 85 thereof, a bar mounted in said loops, and means for removably retaining the bar in position, substantially as described.

3. In a car truck, the combination of side frames, a transverse channel connecting 90 same, a pair of loops struck out of the web thereof, a bar mounted in said loops, and a single vertical pin for retaining the bar in position, substantially as described.

Signed at Chicago, Illinois, this 16th day 95 of March, A. D. 1917.

JOHN W. DALMAN.
